UNITED STATES PATENT OFFICE.

EDWARD JAMES ABBOTT, OF WILTON, NEW HAMPSHIRE.

WINDING MACHINE.

Application filed January 28, 1914. Serial No. 815,083.

To all whom it may concern:

Be it known that I, EDWARD JAMES ABBOTT, a citizen of the United States, and resident of Wilton, in the county of Hillsborough and State of New Hampshire, have invented new and useful Improvements in Winding Machines, of which the following is a specification.

This invention relates to winding machines for winding yarn or thread from one package on to another of more convenient form or size. The invention is applicable to winding machines generally, but it is believed that its largest utility is in connection with winding machines for winding yarn, either in single or multiple ply from the relatively small spools or bobbins upon which it is spun or twisted, into a larger package, usually termed a "cop" or "cheese", which affords a more suitable supply for making various textile products. Such cop or cheese is a package of yarn built up on a suitable yarn receiver, such as a paper or wooden tube or cone made without heads at its ends, the package being held together by the self-binding cross-winding of the yarn as it is laid on. Usually such cop or cheese measures about six inches in length and about six inches in diameter, and requires several bobbins of yarn to make it.

In the winding machine herein illustrated, which is an example of winding machines in general use, as in all winding machines of this type, it has heretofore been necessary for the operator to remove the bobbin supplying the cop, when the bobbin is empty, and to replace it by a fresh bobbin, tie up the ends, and restart the machine, which is usually stopped automatically when the yarn is exhausted from the bobbin. Machines of this character have also been provided with a slug detector which automatically breaks the yarn and stops the machine when a slug, knot or other bunch in the yarn reaches the detector. In such case it has heretofore been necessary for the operator to remove the slug, tie up the ends, and restart the machine.

These operations require in the aggregate a great deal of time and constant attention and labor on the part of the operator in keeping the machine in operation.

The present invention consists in applying to a winding machine mechanism which will operate automatically when the supply from one of the bobbins or other pack-

ages to the winding mechanism ceases, to attach the leading end of the material of a new bobbin or package to the following end of the material passing to the winding mechanism.

As one of the principal uses of the invention is for winding cops or cheeses from bobbins of yarn, I will, for the purpose of illustration, address the description to a winding machine of usual form, and for convenience will use the terms "cop" or "cheese" for the package being wound, "yarn receiver" for the spool, cone or other device on which the material is being wound, and "bobbins of yarn" for the packages of material from which the cop or cheese is supplied. It will be understood, however, that the invention is not limited to any particular form of wound package nor any particular form of supply packages, and that these terms whether used in the specification or claims are intended to designate generically the class of articles of which they are specific examples.

In the preferred form of my automatic yarn replenishing device there is combined therewith means for automatically stopping the machine when the supply of yarn ceases and for restarting the machine after the supply of yarn has been replenished.

Another feature of the invention, not limited, however, to use in conjunction with the yarn replenishing mechanism although it is preferably so used and is herein shown as so used, resides in the provision of automatic mechanism for removing slugs or other bunches from the yarn as the latter passes from the source of supply to the cop or cheese which is being wound. This mechanism comprises a detector for the slug or the like, mechanism to stop the winding operation when the slug appears at the detector, mechanism to remove the slug, mechanism to attach together again the severed ends, and mechanism to restart the machine after the slug has been removed and the ends left by its removal have been tied together. Said slug detecting and removing mechanism is the subject matter of a separate application now Patent No. 1,311,788, dated July 29, 1919.

By the foregoing improvements I have eliminated the greater part of the manual labor and attention on the part of the operator heretofore required in tying in new bobbins when the bobbins being wound are

exhausted, and in taking out the slubs, which work it is estimated has amounted to at least 25% of the whole cost of manufacturing the yarn and preparing it for the warp beam 5 of a loom, or other machine using it.

In the accompanying drawings which illustrate one embodiment of the invention,—

Figure 1 is a side elevation partly in section of a winding machine to which my invention is applied;

Figure 2 is a partial plan view on an enlarged scale of the machine shown in Fig. 1;

Figure 3 is a cross section one line 3—3 15 of Fig. 2;

Figure 4 is a central vertical section through the rotatable creel hereinafter described;

Figure 5 is a section on line 5—5 of Fig. 4;

Figure 6 is a partial section on line 6—6 of Fig. 4;

Figure 7 is an enlarged section on line 7—7 of Fig. 2;

Figures 8 and 9 are details of mechanism 25 hereinafter described;

Figure 10 is a front view of the mechanism shown in Fig. 7;

Figure 11 is a section on line 11—11 of Fig. 10;

Figure 12 is a diagram showing the electrical connections;

Figure 13 is a cross sectional detail of the yarn-severing and knot-tying blade and fingers hereinafter described.

Figures 14, 15 and 16 are partial diagrammatic and sectional views illustrating the relation of the old and new threads or strands to the mechanism at various stages 35 of the operation, as hereinafter explained.

Referring to the drawings, 1 represents the usual holder for the quill or other yarn receiver 2, on which the yarn or thread 3 is wound into a cop or cheese 4. The cop or cheese 4 rests upon a drum 5 and is driven by frictional engagement of the drum with the surface of the cop. The drum 5 is fixed to a shaft 6 which is driven through the usual mechanism, not shown, from the main shaft 7 of the machine. The main shaft 7 is also connected by the usual mechanism, not shown, with the usual cam shaft 8 which carries a cam 9 for actuating thread-guide 10. The foregoing parts are of the usual construction, and it will be understood that the thread-guide 10 is reciprocated lengthwise of the cop on its guide-rods 11 and 12 by means of cam 9, while the cop 4 is rotated by the drum 5. The mechanism thus far described is an example of winding machines in common use, and may if desired also include the usual automatic device, not herein shown, for stopping the winding operation when the cop has grown to a predetermined size.

The yarn is supplied to the cop or cheese

4 from a supply carrier, herein shown as a rotatable creel 13 (Figs. 1, 4, and 5), which is provided with a series of spindles 14 in annular arrangement on the upper side of the creel to receive a plurality of bobbins 70

of yarn or other supply packages 15. The creel 13 as herein shown consists of a circular table rotatably mounted on a central hollow post 16, which is fixed at its lower end in a socket at the top of bracket 17 and therein fastened against rotation by a pin 18. The post 16 is made hollow to receive the wiring for one of the electromagnets hereinafter described. To the hub of creel 13 is fixed the lower end of a sleeve 19 surrounding the post 16 and carrying at its upper end a hollow cylindrical head 20. A flange or ledge 21 is provided on the interior of the cylindrical walls of the head 20, formed on its upper side with ratchet teeth 22, cooperating with a dent 23 which normally rests on the top of flange 21 in the path of the teeth 22. Upon the upper end of the post 16 is mounted a bracket 24 fastened to the post by a pin 25, which also serves as the pivot for detent 23. The bracket 24 is made with a laterally extending arm 26 at its upper end, and an electromagnet 27 is secured to the under side of arm 26. The detent 23

80 constitutes the armature of said electromagnet. When the magnet 27 is energized it

20 Figure 14 is a cross sectional detail of the yarn-severing and knot-tying blade and fingers hereinafter described.

Figure 15 is a partial diagrammatic and sectional view illustrating the relation of the old and new threads or strands to the mechanism at various stages of the operation, as hereinafter explained.

Figure 16 is a partial diagrammatic and sectional view illustrating the relation of the old and new threads or strands to the mechanism at various stages of the operation, as hereinafter explained.

Figure 24 is a partial diagrammatic and sectional view illustrating the relation of the old and new threads or strands to the mechanism at various stages of the operation, as hereinafter explained.

Figure 25 is a front view of the mechanism shown in Fig. 7;

Figure 26 is a section on line 26—26 of Fig. 25;

Figure 27 is a cross sectional detail of the yarn-severing and knot-tying blade and fingers hereinafter described.

Figure 28 is a partial diagrammatic and sectional view illustrating the relation of the old and new threads or strands to the mechanism at various stages of the operation, as hereinafter explained.

head 20 is a radially extending hitching post 39. A yarn detector 31, thread-guide 38 and hitching post 39 are provided for each of the spindles 14 and bobbins 15, and the thread from each bobbin, excepting that from which yarn is being supplied for the time being to form the cop or cheese, extends upwardly between its appropriate detector 31 and clamp plate 37, thence through the thread-guide 38 above said detector to the hitching post 39 above said thread-guide, where the end of the yarn is wound a few times around the post 39 so that the stretch of yarn between the detector 31 and the post 39 will be held taut for the purpose herein-after explained.

The creel 13 rests upon a friction washer 40 of leather, fibre or other suitable material, below which is a beveled gear 41 loosely journaled on post 16 and supported on the top of bracket 17. The bevel gear 41 is continuously driven by a bevel gear 42 fast on shaft 43 carrying at one end a pulley 44 (Fig. 1), which pulley is connected by a belt 45 with the pulley 46 on main driving shaft 7. The continuously driven gear 41 through the friction washer 40 tends to rotate creel 13 in the direction of the arrow in Fig. 2, but is normally held against rotation by engagement of the detent 23 with one of the teeth of flange 21.

When the creel is thus rotated, the taut vertical stretches of yarn held by the detectors 31 and posts 39 are successively presented to the knot-tying and cop-controlling mechanism indicated generally at 47 in Fig. 1, through which the yarn passes from the supply bobbins to the cop or cheese 4. The outer ends of all the detectors 31, excepting the detector of that bobbin which for the time being is supplying yarn to the cop or cheese, are held elevated against the upper edges of their slots 33 by the engagement of their clamps 37 with the yarn, while the outer end of the detector of the bobbin which is supplying yarn to the cop or cheese is also held elevated, but in this case by the draft of the yarn which is moving upwardly between the arm 31 and clamp 37. Thus it will be seen that said arm and clamp constitute a combined detector and tension device for the yarn.

Upon the exhaustion of the yarn on any of the bobbins from which the cop or cheese is being supplied, the relatively heavy outer end of the detector arm 31 drops downward carrying the inner relatively light arm into contact with the conductor segment 30, which closes the circuit through the electromagnet 27. Magnet 27 thereupon lifts detent 23 out of engagement with ratchet teeth 22, allowing the continuously rotating gear 41 to rotate the creel in the direction of the arrow through the friction disc 40, the inner end of the detector arm 31 sliding

upon segment 30. The margin of detector segment 30 is made with a number of gates or notches 48, 49, 50 and 51, angularly separated from one another distances corresponding to the distances between the bobbins on the creel 13. These gates or notches occupy the region of the segment 30 which is traversed by the inner ends of the detectors 31 immediately after their bobbins move away from operative position opposite the head 47.

As the creel 13 rotates, and a full or fresh bobbin is brought into operative position with relation to the mechanism 47, the inner end of detector arm of the empty bobbin reaches and passes upward through one of the gates in segment 30, as shown in dotted lines in Fig. 4, thus breaking the circuit through the magnet 27. This causes the magnet which is now deenergized, to drop the detent 23 in time to engage the next tooth 22 on flange 21, thereby stopping further rotation of the creel.

The following edge 116 of the last gate 51 constitutes the leading end of another ring segment 117, secured to the under side of the flange 28 and insulated therefrom. Segment 117 is out of contact with segment 30. The leading end 116 of segment 117 is bent upwardly to form a cam surface lying in the path of the inner arms of detectors 31 when the latter occupy their dotted line position shown in Fig. 4. When any elevated inner detector arm is moved past the gate 51, it is engaged by the cam end 116 of segment 117 and swung downward into normal position below the flange 28, thereby swinging the detector arm 31 again to normal position.

The mechanism indicated generally at 47 in Fig. 1, is shown in detail in Figs. 7 to 11 inclusive. This mechanism comprises a box-like frame 52 mounted on the machine frame, in which is journaled a hollow shaft 53 which carries three cams 54, 55 and 56, and also a gear 57'. The hollow shaft 53 is normally at rest, but when actuated as presently to be described, it makes one revolution at the completion of which it is automatically stopped. Through hollow shaft 53 extends a continuously rotating shaft 57 on which is fixed a ratchet wheel 58. The shaft 57 is driven by a pulley 59 (Fig. 1) connected by a belt 60 with a pulley 61 fast on the main driving shaft 7. The ratchet wheel 58 cooperates with the pawl 62 pivoted to the cam 54. Said pawl 62 is normally held out of engagement with the ratchet wheel by a hook 63 at the lower end of connecting rod 64. The lower end of the connecting rod 64 is normally held so that its hook 63 supports the pawl 62 in inoperative position by means of a latch 65 pivotally supported by a pintle 66 on the frame 52, and a link 67 pivotally connected

to the lower end of the rod 64 at 68, and at its upper end pivotally connected to the frame 52 at 69. When the latch 65 is disengaged from rod 64, the rod is shifted 5 endwise by a spring 70 in the direction of the ratchet wheel 58, thereby permitting the continuously rotating ratchet wheel to pick up the pawl 62 and carry the latter together with the cam 54 and shaft 53 around 10 with it. The lower end of the rod 64 is forked, and within the fork is mounted a roller 71 engaging cam 54, so that at the completion of one revolution of the shaft 53 and cam 54 the latter pushes the rod 64 outward, thus carrying the shoulder 72 on 15 the rod past the nose of the latch 65 which drops into place under the shoulder and locks the rod 64 again in its original position with the spring 70 under tension. When 20 rod 64 is thus lifted, its hook 63 draws pawl 62 away from the ratchet wheel 58, thereby stopping further rotation of the shaft 53.

To operate the latch 65, a notch 73 is 25 provided which is occupied by the free end of an armature 74 pivoted at 75 on the frame 52. The armature 74 is operated by an electromagnet 76, whose winding is in series with electromagnet 27 within the creel head 20, so that whenever a yarn detector 31 drops 30 and closes the circuit through electromagnet 27, the electromagnet 76 will be simultaneously energized, whereupon the armature 74 will be raised, lifting the pawl 65 and releasing the rod 64 at the same instant when 35 the creel 13 is freed from the detent 23. Thus when the supply of yarn ceases from a bobbin, which for the time being is supplying the cop or cheese, the mechanism is automatically operated, which occasions the 40 step-movement of the creel to present a fresh bobbin to operative position and to cause one revolution of the shaft 53, which in turn stops the winding mechanism and operates the knot-tying mechanism for connecting the 45 leading end of the fresh bobbin with the following end of the yarn passing to the winding mechanism in the manner herein-after described.

Referring now to Figs. 1 and 2, it will 50 be seen that the upper end of rod 64 is pivotally connected to one end of the cylinder segment or shield 77 loosely mounted on shaft 6 and partially surrounding the driving drum 5, said segment being normally held by the rod 64 so that the cop or cheese rests on the driving drum 5. When 55 rod 64 is freed from latch 65 and shifted endwise as described by spring 70, the segmental shield 77 is swung on shaft 6 into a position between the cop and the driving drum 5, thereby lifting the cop out of contact with the driving drum and at the same time acting as a brake to stop the rotation of the cop. Therefore, whenever the shaft 60 53 starts upon its single rotation, the rotation

of the cop or cheese is automatically arrested. When the rod 64 is again lifted by cam 54 at the end of the rotation of shaft 53, it again swings segment shield 77 out from under the cop 4 and permits the 70 cop to be restarted by the continuously driven drum 5.

From the foregoing it will be seen that the dropping of any one of the yarn detectors 31 from the exhaustion or breaking 75 of the yarn, results in energizing both electromagnets 27 and 76, which occasions the simultaneous advance or movement of the creel one step, the rotation of shaft 53 and stoppage of the winding. When, however, 80 the machine acts to detect and remove from the yarn a slab, as presently to be described, only magnet 76 is energized, thereby stopping the winding mechanism and actuating the knot-tying and slab-removing mechanism 85 but leaving the creel 13 unaffected.

The slab detector is shown at 78 and comprises a normally horizontal arm 79 and a relatively heavy upright arm 80 which acts as a counterweight. The detector 78 is pivotally mounted upon but insulated from rod 81 fixed at its ends in the frame 52. The weight of arm 79 is sufficient to hold the detector normally against a stop 82 of insulating material projecting from the frame 52 90 while the free end of the arm 79 occupies a cooperative relation with the abutment 83, also of insulating material fixed to the frame. The yarn from the bobbin or bobbins supplying the cop passes from the creel through the clamp at the outer ends of the yarn detector arms 31, thence through the guiding eyes 38, and thence over a guiding pin 118 (Figs. 7 and 10) and between the abutment 83 and the slab detector arm 79. 100 From the slab detector yarn passes upwardly over a loop-forming guide in the form of a porcelain knob or roller 84, carried by and projecting from the side of a sprocket chain 85. From the loop-forming guide 84 105 the yarn passes downwardly around an arm 86 and through a guiding eye 87 fixed to the frame 52, and thence to the thread-guide 10 of the winding mechanism.

When a slab or other bunch in the yarn 115 strikes arm 79 of the slab detector, the latter is thrown backward until the arm 80 over-balancing the arm 79 makes contact with the hollow shaft 53, thereby closing the circuit through electromagnet 76 stopping the rotation of the cop 4 and causing the shaft 53 to make a single rotation, as above described, without actuating creel 13. This revolution of the shaft 53 acts through mechanism to be described, to remove from the yarn a 120 length or section containing the slab, to tie together the severed ends of the yarn formed by the removal of the slab, and to restart winding. As the shaft 53 approaches the completion of its single revolution the cam 125 130

55 engages arm 80 and restores the slub detector 78 to its normal position.

Upon the top of frame 52 is fastened the lower end of a hollow or tubular casing 88, 5 the lower end of which is open. The upper end of the hollow casing 88 is connected by a pipe 89 with a main suction pipe 90, in which a suction of air is maintained by a blower or other suitable device, so that a 10 strong current of air is constantly flowing upward through the hollow casing 88. The chain 85 above referred to carrying the loop-forming guide 84 is mounted on two sprocket wheels 91 and 92, the former being journaled on a shaft 93 near the upper end of the tubular casing 88, and the lower being fixed to shaft 94 which is journaled in bearings on the frame 52. The shaft 94 carries a pinion 95 (Fig. 7) at one end in mesh with 20 the gear 57 on hollow shaft 53. The ratio between the gears is such that when the shaft 53 makes one complete revolution the sprocket wheel 92 will be driven, in the direction shown by the arrow in Fig. 7, a sufficient distance to move the chain 85 once completely around its path so that the loop-forming guide 84 will make one complete circuit and stop at the point from which it started. Normally the guide 84 on the chain 30 occupies the position shown in Fig. 1 at x , so as to maintain a loop of considerable length in that part of the yarn passing from the supply bobbin to the cop, which is between the detectors and the tying and cutting mechanism.

The arm 86 is loosely mounted on a vertical rock shaft 96, but is connected with said shaft through a spring 97 which normally tends to hold the arm 86 against a stop pin 40 102 on the arm 52. The rock shaft 96 carries a pair of arms 98 and 99 one above the other, and at its lower end carries a laterally projecting cam roll 100 which is held against cam 56 by a spring 101 connecting a lever on arm 99 with the frame 52.

When the creel 13 is actuated as described to advance one step, one of the taut stretches of yarn on the head 20 of the creel is carried between abutment 83 and arm 79 of 50 the slub detector and between the two arms 86 and 98 and behind the arm 99. Immediately thereafter the cam 56 acts through cam roll 100 to rock the shaft 96 and swing the two arms 98 and 99 in the direction of the mechanism 47 so as to carry that stretch of the yarn which extends between said arms into the same path as the active or old yarn running about guides 86 from casing 88 or guide 84, and to take both old and new yarns into position to be acted upon by the knot-tying and yarn-severing devices.

During the first part of the movement of the arms 98 and 99 the arm 86 will be held against stop pin 102 by the spring

97, so that the arms 98 and 86 will be closed together to clamp the yarn between them, after which the continued movement of arm 98 will swing the arm 86 with it as a single part to the limit of movement in the direction of the knot-tying and severing devices.

Referring now to the knot-tying and yarn-severing devices contained in the head 47, 103 represents a bushing fastened by a screw 104 in a hole provided therefor in the frame 52. Within this bushing 103 is journaled a stem 105 of the knot-tier and yarn cutter. A longitudinal slot is provided in the operative end of said stem 80 in which is arranged a yarn-cutting and gripping blade 107. The blade 107 is pivoted at 108 in the fork of the stem 105, and is made with a tail-piece 106 which works in an eccentric or cam-like recess 85 107^a in the end of bushing 103, so that as the stem 105 is rotated the said eccentric recess acts to swing the blade on its pivot 108 to open and close the blade with relation to the fingers at the end of stem 105. 90 At the opposite end of stem 105 is fixed a pinion 109 which is driven through an intermediate gear 110 by the gear 57 on shaft 53. The operative end of stem 105 is made with two obliquely disposed tapering fingers 111 and 112, one at each side of the blade 107. Finger 112 cooperates with the sharp or cutting edge 113 of blade 107 to cut the yarn when the blade is closed with relation to the fingers, and the other finger 111 cooperates with the rounded edge 114 of the blade to clamp the yarn between the blade and finger 111 when the blade is closed. Normally the oblique fingers and blade occupy the position best shown in 95 Figs. 10, 11 and 13 which is diametrically opposite to the position which they will occupy when the arms 86, 98 and 99 swing the yarn into cooperative relation with said tying and cutting mechanism. The arrangement of the cams and the action of the parts is so timed that after the creel has brought a new bobbin into position, and the arms 86, 98 and 99 have swung the taut stretch of that bobbin and of the old or previous yarn into cooperative relation with the stem 105, the latter has been rotated to a position such that the arms 98 and 99 lay the taut stretch of the yarn against the stem 105 within the acute angle formed 115 back of the fingers 111 and 112. At the end of the next quarter revolution of the stem 105 and while the fingers 111 and 112 are passing the stretch of yarns extending from the stem 105 to the arm 98, the blade 107 is held closed by the cam recess 107^a, so that as the fingers 111 and 112 pass that stretch of the yarn, the yarn is 120 engaged by the outer sides of the fingers and deflected around the end of stem 105. 125

At the end of one complete revolution of the stem 105 the yarn has been wound one turn around the stem close to the bases of the fingers 111 and 112.

6 During the next or fifth quarter of the revolution of stem 105 the fingers and blade 107 reach that stretch of the yarns extending from stem 105 to the arm 99 and the blade 107 occupies its most open position
10 so that continued movement of the stem lays the yarns into the V-shaped opening between the blade and the fingers and thereafter closes the blade upon the yarns, the sharp edge of the blade severing the yarns
15 between the blade and arm 99 and the other edge of the blade clamping the ends of the yarns coming from the knot which is being formed. As the stem starts the last half of its second revolution and while the
20 blade is still closed, the arms 86 and 98 stop and start to move back toward their normal positions, and in so doing pull upon the yarns extending from said arms to the knot and act to pull the knot off from the
25 stem and fingers and to draw it tight. As the stem approaches the latter part of its second revolution the blade 107 is fully open and the tied ends of the yarn are left in the grip of the arms 86 and 98 which are moving backward toward their normal position.

During these operations the sprocket chain will have been actuated by gear 57, intermediate gear 110 and gear 109 on the sprocket shaft 94, to make one complete revolution. The parts are so timed that as arm 86 strikes stop pin 102 and arm 98 moves away from arm 86, the loop-forming guide roller 84 on the sprocket chain will 30 pass upward between said two arms (see Fig. 8) and pick up the yarn. After picking up the yarn the guide roller 84 is carried to its normal position by the sprocket chain, forming a new loop which extends 35 upward into the tubular casing 88 as above described. The purpose of this loop is to provide a sufficient length of yarn between the detectors 31 and 78 and the roller guide 40 84, and between said guide 84 and the bottom of tubular casing 88, to prevent the end 45 of the yarn which is passing to the cop or cheese from moving out of the lower end of the tubular casing 88 and out of the range of the knot-tier before the rotation of the cop is stopped by the action of the yarn 50 detectors 31, and in the case of operation to remove a slub, to insure that the slub detector 78 will stop the machine while the slub is somewhere in the loop which occupies 55 the tubular casing 88 when the movement of the yarn ceases. It follows, therefore, that whether the winding mechanism is stopped by the exhaustion of the yarn through 60 the operation of the yarn detector 31, or by the appearance of a slub through 65

the operation of the slub detector 78, the yarn end or the slub, as the case may be, will be within said tubular casing 88. If the winding mechanism is stopped by the exhaustion of the yarn, the following end 70 of the yarn will be held up within the tubular casing 88 by the air draft therein. When the creel is actuated to bring the leading end of the yarn of a fresh bobbin into tying position, said leading end is thus brought 75 along side of the following end of the yarn passing to the winder about arm 86, whether or not the exhausted or broken end is supported in the tubular casing 88 by the air current only, or is long enough still to extend 80 around roller 84 and past the arms 98 and 99, and the knot-tying mechanism will act upon the new and old strands to unite them by tying in the knot as above described as if they were one strand. 85

When the blade 107 severs from the knot formed on stem 105, that portion of the yarn or yarns which is held above it in the tubular casing 88, the severed portion is carried off by the air current through pipes 90 89 and 90.

In case the winding operation is stopped through the slub detector 78 the slub will have reached some point in the loop held up within the tubular casing 88 by the loop-forming guide 84, and while in such position the arm 98 and the knot-tying mechanism will operate respectively to bring together and to tie the two legs of the loop together, and then sever from the leading and following portions of the yarn that section of the loop containing the slub above the knot, said severed section being carried off through pipes 89 and 90, while the roller guide 84 on chain 85 will descend to pick up the reunited yarn and again rise to form a new loop ready for another operation. 100

The guide eye 87 is offset from the chain 85 as best shown in Fig. 11, so that the length of yarn between arms 86 and said guide eye will not be picked up by the loop-forming guide 84 during its downward movement. 110

If only a single strand of yarn or thread is to be wound upon the cop it will be sufficient if there is a single conductor segment 30 and gate 48 to break the circuit through the electromagnet. In such event, however, the gate 48 should be made sufficiently wide so that the detectors 31 will remain in the gate for several steps in the movement of the creel. It is the practice, however, often to wind two or more strands of yarn simultaneously upon the cop or cheese, and for this purpose I provide a plurality of angularly separated gates 48, 49, etc., as shown. When winding two strands, for example, one supply bobbin will occupy its regular running position directly under the slub detector 78, while the sec- 120 125 130 135

ond supply bobbin will be the next bobbin on the creel in advance of the one under the slub detector. The thread or yarn from the second bobbin will extend from its guide 5 38 around the guide-pin 118 where it will join and pass upward alongside of the yarn from the first bobbin. Under these conditions the draft on the two upwardly moving strands of yarn holds their respective detectors 31 elevated, and when either 10 yarn runs out or when a slub appears in either yarn, the yarn detector or the slub detector as the case may be, will act as already described to tie in a fresh strand of 15 yarn or to cut out the length of yarn containing the slub, and retie the ends. It will be understood that where several strands are thus used they all lie side by side and are acted upon by the tying and 20 cutting mechanisms as a single strand,

In Figure 12 I have illustrated diagrammatically the wiring and electrical connections for controlling the mechanisms hereinbefore described. The battery or source 25 of electrical energy is shown at 122. One pole of the battery 122 is connected by a wire 119 with one end of the winding of electromagnet 76. The other end of the winding of electromagnet 76 is connected 30 by wire 120 with one end of the winding of magnet 27. The other end of the winding of magnet 27 is connected by wire 121 with the conductor segment 30. The opposite pole of battery 122 is connected by wire 35 123 with the frame of the machine, on which the shaft 53 and detectors 31 are grounded. The slub detector 78 is insulated from the frame 52 and is connected by a wire 124 with the wire 120. It will thus be seen 40 that when the detector 78 is operated by a slub and makes contact with the hollow shaft 53, the circuit is closed only through magnet 76, but when the detector 31 is operated by the exhaustion of the supply of 45 yarn and makes contact with conductor segment 30, the circuit will be closed through both magnets 76 and 27.

The relation between the thread or yarn and the parts of the mechanism acting upon 50 the yarn at various stages in the operation above described, is shown diagrammatically in Figs. 14, 15 and 16. Fig. 14 illustrates the condition of things when the yarn has run out from a bobbin, the material passing 55 from arm 86 to the winding machine being designated as "active thread," the yarn end still in casing 88 being designated as "exhaust end," and the bobbin from which said yarn has been drawn being designated 60 as "empty bobbin." The detector 31 has fallen to operate the mechanism for turning a new or full bobbin into place. Fig. 15 shows the position of the parts when a full bobbin has been turned into running position, with the

leading end of its yarn alongside the exhaust 65 end of the preceding strand ready to be tied. And Fig. 16 shows the knot tied, the clamping arms again opened, and the loop-forming guide roller 84 starting from the lower 70 end of its travel to rise and draw up a new loop in the tied yarn. The cut off ends will at this stage have been drawn away by the air suction in casing 88.

I claim:—

1. In combination, winding mechanism, 75 a supply package carrier holding a plurality of packages of yarn to be unwound, breakage or exhaustion detectors and tying mechanism controlled by said detectors operating automatically whenever the supply from one of said packages to the winding mechanism ceases, then to tie together the leading end 80 of the yarn in another package to the following end of the yarn passing to the winding mechanism.

2. A winding machine comprising a yarn receiver, a supply bobbin holder adapted to carry a plurality of bobbins of yarn from which the yarn receiver is supplied, and mechanism having a detector element co-operating with the unwinding yarn in the vicinity of said bobbin holder, and operated automatically, by and upon cessation of the supply from a bobbin to the yarn receiver, 90 to tie the leading end of the yarn on another bobbin to the following end of the 95 yarn passing to the yarn receiver.

3. A winding machine comprising a rotary yarn receiver, a bobbin holder adapted to carry a plurality of bobbins of yarn from which the yarn receiver is supplied, and mechanisms operated automatically, upon the occurrence of and as a consequence of cessation of the supply from a bobbin 100 to the yarn receiver, to stop the rotation of the yarn receiver and to attach the leading end of the yarn on another bobbin to the following end of the 105 yarn passing to the yarn receiver.

4. A winding machine comprising a rotary yarn receiver, a bobbin holder adapted to carry a plurality of bobbins of yarn from which the yarn receiver is supplied, and mechanism operated automatically, when the supply from a bobbin to the yarn receiver ceases, to stop the rotation of the yarn receiver and concurrently to attach the leading end of the yarn on another bobbin to the following end of the 110 yarn passing to the yarn receiver, and thereafter to restart the 115 yarn receiver.

5. A winding machine comprising a rotary yarn receiver, a bobbin holder adapted to carry a plurality of bobbins of yarn from which the yarn receiver is supplied, a yarn detector actuated when the supply from a bobbin ceases, and mechanism actuated by 120 and upon operation of the yarn detector to 125

attach the leading end of the yarn on another bobbin to the following end of the yarn passing to the yarn receiver.

6. A winding machine comprising a rotary yarn receiver, a bobbin holder adapted to carry a plurality of bobbins of yarn from which the yarn receiver is supplied, a yarn detector actuated when the supply from a bobbin ceases, and mechanism controlled by the yarn detector to stop the rotation of the yarn receiver, and concurrently to attach the leading end of the yarn on another bobbin to the following end of the yarn passing to the yarn receiver, and to restart the yarn receiver.

7. A winding machine comprising a rotary yarn receiver, a bobbin holder adapted to carry a plurality of bobbins of yarn from which the yarn receiver is supplied, tying mechanism, in operative proximity to yarns running from said bobbins to said receiver and means operated automatically, when the supply from a bobbin to the receiver ceases, to present another bobbin to the tying mechanism, and to operate the tying mechanism to attach the leading end of the yarn from the latter bobbin to the following end of the yarn passing to the yarn receiver.

8. A winding machine comprising a rotary yarn receiver, a bobbin holder adapted to carry a plurality of bobbins of yarn from which the yarn receiver is supplied, tying mechanism, and means operated automatically, whenever the supply from a bobbin to the yarn receiver ceases, to stop the rotation of the yarn receiver, to present another bobbin to the tying mechanism, to operate the tying mechanism to attach the leading end of the yarn from the latter bobbin to the following end of the yarn passing to the yarn receiver, and to restart the yarn receiver.

9. In combination, winding mechanism, a rotary creel adapted to carry a plurality of bobbins of yarn for supplying the winding mechanism, and mechanisms operated automatically, when the supply from one of said bobbins to the winding mechanism ceases, to rotate the creel and present another bobbin to operative position, and attach the leading end of the yarn on the latter bobbin to the following end of the yarn passing to the winding mechanism.

10. In combination, winding mechanism, a rotary creel adapted to carry a plurality of bobbins of yarn for supplying the winding mechanism, and mechanisms operated automatically when the supply from one of said bobbins to the winding mechanism ceases, to stop the winding mechanism, to rotate the creel and present another bobbin to operative position, to attach the leading end of the yarn on the latter bobbin to the following end of the yarn passing to the

winding mechanism, and to restart the winding mechanism.

11. In combination, winding mechanism, a rotary creel adapted to carry a plurality of bobbins of yarn for supplying the winding mechanism, a yarn detector for each bobbin mounted on said creel, each yarn detector being actuated when the supply from its bobbin ceases, and mechanism operated by the yarn detector of the bobbin which for the time being is supplying the winding mechanism, to rotate the creel and present another bobbin to operative position, and to attach the leading end of the yarn on the latter bobbin to the following end of the yarn passing to the winding mechanism.

12. A winding machine comprising a rotary yarn receiver, a movable supply package carrier adapted to carry a plurality of packages of yarn from which the yarn receiver is supplied, tying mechanism, and means operated automatically, when the supply from a package to the yarn receiver ceases, to present another package to the tying mechanism, and to operate the tying mechanism to attach the leading end of the yarn from the latter package to the following end of the yarn passing to the yarn receiver.

13. In combination, winding mechanism, a carrier holding a plurality of packages of material to be wound, a material detector, loop-forming mechanism to form a loop in the material between the detector and the winding mechanism, means operated by the material detector when the supply from a supply package ceases, to place the end of the material from a fresh supply package along side of the material in the loop, tying mechanism opposite said loop adapted to act upon both the material in the loop and the material from the fresh package, and mechanism automatically operated by said detector to actuate the tying mechanism.

14. In combination, winding mechanism, a carrier holding a plurality of packages of material to be wound, means on said carrier to hold a stretch of the material at the leading end from each package taut for presentation to the tying mechanism, a yarn detector for each package, loop-forming mechanism to form a loop in the material between the detector and the winding mechanism, tying mechanism opposite said loop, and mechanisms operated automatically by the detector, when the supply from a package of material to the winding mechanism ceases, to present the taut stretch of yarn from another package to the tying mechanism, along side of said loop, and to actuate the tying mechanism to attach the two yarn ends together.

15. In combination, winding mechanism, a carrier holding a plurality of packages of

- material to be wound, means on said carrier to hold a stretch of the material at the leading end from each package taut for presentation to the tying mechanism, a yarn detector 5 for each package, loop-forming mechanism to form a loop in the material between the detector and the winding mechanism, tying mechanism opposite said loop, and mechanisms operated automatically by the detector when the supply from a package of material to the winding mechanism ceases, to stop the winding mechanism before the material runs out of said loop, to present the taut stretch of yarn from another 10 package to the tying mechanism along side of said loop, and to actuate the tying mechanism to attach the two yarn ends together and to restart the winding mechanism.
16. In combination, winding mechanism, a carrier holding a plurality of packages of material to be wound, means on said carrier to hold a stretch of the material at the leading end from each package taut for presentation to the tying mechanism, a yarn detector 20 for each package, loop-forming mechanism to form a loop in the material between the detector and the winding mechanism, tying mechanism opposite said loop, swinging arms to carry said taut stretch of material alongside of the material in said loop, and mechanisms operated automatically by the detector when the supply from a package of material to the winding mechanism ceases, to advance said carrier and present a fresh 30 package into operative position, to actuate said swinging arms, and to actuate said tying mechanism.
17. In combination, winding mechanism, a supply of material to be wound, automatic 40 tying mechanism, and means to form a loop in the material between the supply and the winding mechanism comprising a movable guide adapted after each operation of the tying mechanism to pick up said material and form a loop therein.
18. In combination, winding mechanism, a supply of material to be wound, automatic 50 tying mechanism, and means to form a loop in the material between the supply and the winding mechanism comprising a movable guide carried by a sprocket chain or belt, adapted after each operation of the tying mechanism to pick up said material and form a loop therein.
- 55 19. In combination with a winding mechanism and tying mechanism, a rotatable creel for carrying a plurality of bobbins of yarn, a creel head mounted on said creel, a series of yarn detectors pivoted on said creel head, one for each bobbin, and a series of hitching posts on said creel head, one for each bobbin, adapted to hold the yarn stretched between said detectors and posts for presentation to the tying mechanism.
- 60 20. In combination with a winding mechanism and tying mechanism, a rotatable creel for carrying a plurality of bobbins of yarn, a creel head mounted on said creel, a series of yarn detectors pivoted on said creel head, one for each bobbin, an electromagnet 70 for controlling the rotation of said creel, and a circuit for said magnet controlled by said pivoted detectors.
21. In combination with a winding mechanism and tying mechanism, a rotatable creel for carrying a plurality of bobbins of yarn, a creel head mounted on said creel, a series of yarn detectors pivoted on said creel head, one for each bobbin, an electromagnet 75 for controlling the rotation of said creel, and a stationary contact segment in circuit with said electromagnet and in the path of said detectors, said detectors adapted when actuated by the exhaustion of the yarn to make contact with said segment and close the circuit through said electromagnet.
22. A winding machine having therein a receiver upon which material is wound during operation, a carrier for a plurality of supply packages from each of which the material may be wound, and means on said carrier to detect breakage or exhaustion of the unwinding material upon the occurrence thereof, in combination with means actuated by and upon operation of said detector means for joining a new strand from one of said packages to the exhausted or broken end, whereby to continue winding upon said receiver.
23. A winding machine having therein a receiver upon which one or more strands are wound during operation, a carrier for a plurality of supply packages from each of which the material may be wound, and means to detect breakage or exhaustion of any strand of the unwinding material at said carrier upon the occurrence thereof, in combination with means actuated by and upon operation of said detector means for joining a new strand or strands from one or more of said packages to the exhausted or broken end, whereby to continue winding upon said receiver.
24. A winding machine having therein a receiver upon which material is wound during operation, a carrier for a plurality of supply packages from each of which the material may be wound, and means to detect breakage or exhaustion of the winding material, in combination with means actuated by and upon operation of said detector for stopping winding on said receiver and tying a new strand or strands of the material from one or more of said packages to the exhausted or broken end, whereby to continue winding upon said receiver.
25. A winding machine having therein a receiver upon which material is wound during operation, a carrier for a plurality of supply packages from each of which the ma-

terial may be wound, means to detect breakage or exhaustion of the winding material, and means actuated by said detector to stop winding upon said receiver, in combination 5 with means concurrently actuated upon operation of said detector for tying a new strand or strands of the material from one or more of said packages to the exhausted or broken end, whereby to continue winding 10 upon said receiver.

26. A winding machine having therein a receiver upon which material is wound during operation, a carrier for a plurality of supply packages from each of which the material 15 may be wound, means to detect breakage or exhaustion of the winding material, means actuated by said detector to stop winding upon said receiver, in combination with means concurrently actuated 20 upon operation of said detector for tying a new strand or strands of the material from one or more of said packages to the exhausted or broken end, and means to start winding upon said receiver upon completion 25 of the tying operation, whereby to continue winding upon said receiver.

27. A winding machine having therein a receiver upon which a strand of material is wound during operation, a carrier for a plurality of supply packages from which the material 30 may be wound, and means to detect breakage or exhaustion of an unwinding strand, in combination with means actuated by operation of said detector means for moving the carrier to position a new package 35 for attachment of a strand therefrom to the end of the exhausted or broken strand.

28. A winding machine having therein a receiver upon which a strand of material is wound during operation, a rotary carrier for a plurality of supply packages from which the material may be wound, means to detect breakage or exhaustion of the unwinding strands, in combination with means actuated 40 by operation of said detector for moving the carrier to position a new package for attachment of a strand therefrom to the end of the exhausted or broken strand, and tying means actuated upon operation of said detector for joining the new strand to said broken or exhausted strand.

29. In combination, winding mechanism, a supply package carrier holding a plurality of packages of yarn to be wound, breakage or exhaustion detector means associated with the supply package carrier, and means automatically actuated by said detector means for joining the leading end of one package on said carrier to the following exhausted or broken end of another package on said carrier upon the occurrence of breakage or exhaustion.

30. In combination, winding mechanism, a movable supply package carrier holding a plurality of packages of yarn to be wound,

breakage or exhaustion detector means movable with the supply package carrier, and means automatically actuated by said detector means for joining the leading end of one package on said carrier to the following exhausted or broken end of another package on said carrier upon the occurrence of breakage or exhaustion. 70

31. An automatic replenishing mechanism for a winding machine comprising a creel having therein packages of fresh supplies of the material to be wound, a series of detector devices each operating upon breakage or exhaustion of the material in one of said packages, and means actuated by and upon operation of any of said detectors to tie together the end of the material causing operation of said detector to the leading end of material in a fresh supply package. 75

32. A winder having, in combination, a stationary normally-idle knotter having a tying bill and thread-guides adapted to position threads in relation to the bill, a thread-carrier movable step by step, and a series of pairs of supports on said carrier to support a series of threads, each pair being arranged to support a thread-portion extending between the members of said pair transversely of the direction of movement of the carrier, said guides being located in the path of movement of such transverse thread-portions. 80

33. A winder having, in combination, detectors to detect exhaustion of the threads being wound, a stationary normally-idle knotter, and a thread-carrier supporting a series of threads and movable step by step to carry threads singly and successively into operative relation to the knotter, the movement of the carrier and the operation of the knotter being controlled by the detectors. 100

34. A winder having, in combination, detectors to detect exhaustion of the threads being wound, a stationary normally-idle knotter having a tying bill and thread-guides at each side of the bill, a thread-carrier movable step by step, the movement of the carrier being controlled by the detectors, and a series of supports on said carrier to support a series of threads, a portion of each thread extending transversely of the direction of movement of the carrier, and the guides being located in the path of movement of such transverse thread-portions and adapted to position the threads in relation to said tying bill. 115

35. A winder having, in combination, means for holding an active and a reserve thread supply; means for holding the end of the reserve thread; means for rotating a winding carrier upon which the active thread is wound; a normally idle knotter stationarily located with respect to said winding carrier and in the vicinity of the end of the reserve thread and of the run- 125 130

ning active thread on its way to the winding carrier; and a detector controlled by the active thread and acting, when the supply of said thread is exhausted, to initiate the 5 action of said knotter, whereby said threads are tied together.

36. A winder having, in combination, means for holding an active and a reserve 10 thread supply; means for holding the end of the reserve thread; means for rotating a winding carrier upon which the active thread is wound; normally idle thread uniting means stationarily located with respect to said winding carrier and in the vicinity 15 of the end of the reserve thread and of the running active thread on its way to the winding carrier; and a detector controlled by the active thread and acting, when the supply of said thread is exhausted, to initiate the 20 action of said thread-uniting means.

37. A winder having, in combination, a support for an active thread supply, a support for a reserve thread supply, winding means, a knotter in proximity with which the active thread runs to the winding means, means actuated upon exhaustion of the active thread for moving the reserve thread into operative relation to the knotter and for clamping both threads, and means for actuating the knotter after said threads have been clamped.

38. A winder having, in combination, a replenishment yarn supply holder adapted to be moved to present a new supply two guides for the thread being wound, a normally-stationary device movable into position to engage the thread at a point between the guides and movable into position to draw the thread into the form of a reserve-supply 40 loop, and means for moving said device into position thus to engage the thread upon actuation of said holder.

39. A winder having, in combination, means for supporting a winding couple, said means including a movable support for the unwinding member of the couple, a detector engaging the thread of the couple, adjacent to said unwinding member and a clamp arranged to clamp the thread at a point between the detector and the receiving member of the couple, said clamp being controlled by the detector.

40. A winder having, in combination, a 55 rotatable magazine for supporting thread carriers before, during and after unwinding, a series of devices rotating with the magazine for holding the ends of the threads on the thread carriers, a device for taking the threads singly, and means for turning the magazine and said series of holding devices to carry the threads successively into operative relation to the thread-taking device.

41. A winder having, in combination, a 60 stationary knotter, a rotatable thread-mass

magazine, means for moving a thread of one of the thread-masses into proximity to the knotter, and means for turning the magazine to bring successive threads within reach of said means.

42. Automatic replenishing winding mechanism having therein means for rotating a winding carrier, a knot-tying mechanism, a rotatable creel for supporting a series of supply bobbins, including an active unwinding bobbin, guiding means for the active yarn causing it to pass in operative relation to the knot-tying mechanism, means actuated by and upon cessation of supply of the active yarn to rotate the creel and thereby to present the end of a fresh supply of yarn on one of said bobbins in operative relation to said knot-tying mechanism, and means for automatically actuating the knot-tying mechanism to tie together the ends of ceasing active and the fresh supply yarn.

43. Winding mechanism having therein a creel rotatable on a vertical axis and adapted to carry a plurality of bobbins of yarn for supply the winding mechanism, means operating automatically when the supply from one of said bobbins in an operative position ceases to rotate the creel and presents another bobbin and the leading end of its yarn in operative position, a normally idle knotter, and means for operating the knotter to tie the leading end of the yarn from the bobbin in said operative position to the following end of the yarn passing to the winding mechanism.

44. Automatic replenishing winding mechanism having therein a winding carrier and means for driving the same, a knot-tying mechanism, a rotatable creel carrying a concentric series of supply bobbins to be unwound, supply yarn end-holders on the creel for holding the ends of the yarn supplies in concentric relation to the axis of rotation of the creel and in position to be moved in turn into operative relation to the knot-tying mechanism on rotation of the creel, and means for rotating the creel and actuating the knot-tying mechanism to tie a fresh supply yarn end to the following end of an exhausted or broken active thread upon occurrence of breakage or exhaustion.

45. A winder having, in combination, means for rotating a winding carrier, a knotter for tying a new thread to the thread being wound, a shaft for driving the knotter, means to rotate the shaft, and means on said shaft for discontinuing the rotation thereof upon the completion of one cycle of operations of the knotter.

46. A winder having, in combination, means for rotating a winding carrier, means for stopping the rotation of the winding carrier upon exhaustion of the thread being wound, a knotter for tying a new thread on the thread being wound, a shaft for dry-

ing the knotter, means to rotate the shaft, and means for causing the winding carrier to resume rotation upon the completion of one cycle of operations of the knotter.

5. 47. A winding machine having therein, in combination, means for rotating a winding carrier for winding; means for stopping and for subsequently restarting the rota-

tion of the winding carrier; means for detecting exhaustion of the threads being wound; and means whereby the means for detecting exhaustion control said stopping and restarting means. ¹⁰

Signed by me at Boston, Massachusetts, this 22d day of January, 1914.

EDWARD JAMES ABBOTT.
